UNITED STATES PATENT OFFICE.

BEDFORD C. WYSONG, OF INDIANAPOLIS, INDIANA.

GAS MIXER FOR INTERNAL-COMBUSTION ENGINES.

Application filed February 26, 1921. Serial No. 447,983.

To all whom it may concern:

Be it known that I, BEDFORD C. WYSONG, a citizen of the United States, and a resident of Indianapolis, county of Marion, and State 5 of Indiana, have invented a certain new and useful Gas Mixer for Internal-Combustion Engines; and I do hereby declare that the following is a full, clear, and exact description thereof, reference being had to the 10 accompanying drawings, in which like numerals refer to like parts.

This invention relates to a gas mixer for the intake of an internal combustion engine and is adapted to be interposed between the 15 intake manifold and the carburetor.

The chief object of the invention is to provide a mixer which will break up further the volatilized fuel and thoroughly mix the same after said fuel has been discharged 20 from the carburetor into the intake.

The chief feature of the invention consists in the particular means for mixing the fuel and the positioning of the same in the intake.

Another feature of the invention consists 25 in the particular mounting of the mixer, whereby the same may be readily associated between the carburetor and intake connections so as to constitute a gasket between the 30 companion flanges of said connections.

Another feature of the invention consists 35 in the particular construction of the mixing element.

The full nature of the invention will be 40 understood from the accompanying drawings and the following description and claims.

In the drawings, Fig. 1 is a side elevational view of an internal combustion engine 45 of a motor vehicle including a carburetor and showing the invention associated therewith. Fig. 2 is a plan view of the invention detached from the internal combustion engine. Fig. 3 is a central cross sectional view 50 of the invention taken on line 3—3 of Fig. 2.

In the drawings Fig. 10 indicates an internal combustion engine having an intake manifold 11 and an intake pipe 12 with which is associated a carburetor 13. The intake 11 and pipe 12 are provided with companion flanges 14 which are secured together by means of the bolts 15 to rigidly secure the carburetor to the intake of the internal combustion engine.

The mixing device constitutes an attach-

ment for the foregoing and comprises a gasket body portion 16 of substantially elliptical form provided with a pair of bolt openings 17 along the major axis. Centrally positioned in said elliptical body portion is a central opening 18. It is to be understood that the central opening 18 registers with the carburetor discharge opening and the intake opening, and the gasket 16 is substantially the same shape in outline as the companion flanges 14 such that the gasket registers with said companion flanges and is adapted to be positioned therebetween by means of the bolts 15 passing through the registering bolt openings 17 such that when 60 said bolts are tightened, the gasket body portion will be rigidly secured between the carburetor and the intake of the engine.

The mixing element is rotatably supported by the elliptical body portion and herein 70 is shown comprising a circular plate with a serrated edge and, is provided with bent tips 20 shown in cross section in Fig. 3 so as to increase the propeller action thereof. The central portion of the plate 19 is perforated 80 or foraminated by means of a plurality of small holes 120. It is to be understood that the curved and foraminated plate 19 is rotatably mounted so as to revolve about one of its diameters. It is to be further understood 85 that the rotatable mounting may be positioned anywhere within the central opening 18 of the elliptical gasket 16. The rotatable mounting preferably is along or coincides with minor axis of said elliptical gasket. 90

Herein the preferred means for rotatably supporting the perforated and curved mixing plate comprises a spindle or shaft 21 which may or may not be rigid with the plate 19. Said shaft or spindle is provided 95 with conical points 22, and there is provided in the body portion 16 conical seats 23 for said conical points 22. In the present invention said seats are formed in the end of a bolt 24 having a threaded engagement with 100 the gasket 16 in the opening 25 thereof. The bolt 24 is adjusted along the minor axis by means of the screw head 26 and a lock nut 27 rigidly secures said bolt in the adjusted position.

It is to be understood that as illustrated 105 the preferred form of the invention is such that the bands in the tips of the plate do not exceed in width the thickness of the gasket 16 such that the device may be in- 110

serted as a unit between the companion flanges 14 and readily secured thereto with but little difficulty.

The invention claimed is:

- 5 1. A gas mixer for the intake of an internal combustion engine, including a body portion having an opening registering with said intake, a plate rotatable about its diameter having a plurality of perforations in the central portion thereof, and means for 10 rotatably supporting said plate within said body portion.
2. A gas mixer for the intake of an internal combustion engine, including a body 15 portion having an opening registering with said intake, a plate rotatable about its diameter having a plurality of perforations in the central portion thereof, and adjustable

means mounted in said body portion for rotatably supporting said plate therein.

3. A gas mixer for the intake of an internal combustion engine, including a body portion having an opening registering with said intake, a circular plate rotatable about its diameter having a plurality of perforations in the central portion thereof, and adjustable means for rotatably supporting said plate in the opening of said body portion, the axis of rotation of said plate extending diametrically therethrough at right angles to the direction of flow of the gas 25 passing through said opening.

In witness whereof, I have hereunto affixed my signature.

BEDFORD C. WYSONG.
